UNITED STATES PATENT OFFICE

JACOB L. KLEINMAN, OF NEW YORK, N. Y.

RAZOR

Application filed May 9, 1932. Serial No. 610,240.

This invention relates to razors, blade holders and razor blades, and more particularly to razors and blades of the safety type.

A primary object of this invention is to provide a razor wherein the blade can be readily adjusted and the edges thereof will move freely and be tilted to any angle desired, to vary the fineness of the cut or shave, without loosening the parts which hold the blade in position.

Another object of this invention is to provide a blade so constructed that it possesses superior strength and resilience.

A still further object of this invention is to provide a safety razor wherein although the handle and associated parts are securely clamped together, yet the angle of the blade may be controlled and the edges thereof move freely and be tilted without affecting the degree of such clamping.

Still another object is to provide a blade holder assembly, consisting of a handle and two clamping members for holding the blade, and at least one of said members having a moveable carrier permanently mounted therein, so that the carrier and member actually become one unit.

Yet a further object is to provide a safety razor and a blade of a type that is practical, durable and convenient in use, simple in construction, and economical to manufacture.

Other objects and advantages of the present invention will appear from the description thereof to follow, taken in connection with the accompanying drawing, in which—

Fig. 1 is an assembled view of the razor and blade, embodying my present invention, partly broken away to show more clearly the normal position of the blade.

Fig. 2 is a view similar to Fig. 1, but shows at the limit of adjustment of the blade.

Fig. 3 is a cross-sectional view on the plane indicated by the line 3—3 of Fig. 1.

Fig. 4 is a side view of the top member of the assembly shown in Fig. 1;

Fig. 5 is a bottom plan view of the member shown in Fig. 4;

Fig. 6 is a plan view of the intermediate member upon which the blade is adapted to rest;

Fig. 7 is a plan view of the blade;

Fig. 8 shows a detail of the carrier;

Fig. 9 shows one of the clamping members and the carrier in assembled form as a unit, and

Fig. 10 shows a modified form of Figs. 1, 2 and 3.

Referring to the drawing; 5 indicates a curved upper clamping member to which is fitted a screw 6 having a base 7. The screw 6 and base 7 are provided with a slot 8 for a purpose to be set forth hereinafter. A blade 9 having an aperture 10, (larger in size than the base 7), is associated with the member 5. A bridge 10' divides said aperture 10 into two separate openings positioned at each side of said bridge 10', said bridge is also adapted to be positioned in the slot 8 of screw 6, thereby preventing the rotation of said blade 9, the edges 11 of opening 10 being bent to one side, so that they slide smoothly over the threads 12 of screw 6 until said opening 10 receives the base 7, when the blade is fitted on the member 5. A carrier 14 is mounted on the lower clamping member or plate 15, 65 the carrier having extensions 16 loosely fitted within slots 17 in the plate 15, the outer ends of extensions 16 are struck down or expanded by a suitable tool, as shown at 18 to prevent the separation of carrier 14 from plate 15. 70 Carrier 14 and plate 15 thus actually becomes a single unit as indicated by arrow 15' (see Fig. 9). This unit 15' is then placed upon the blade 9; an opening 19 in plate 15 permits screw 6 to pass through it until said 75 opening 19 reaches base 7, at the same time the bridge portion 20 of carrier 14 is being automatically positioned in slot 8 of screw 6 and base 7, thereby preventing the rotation of said unit 15', and the upper surface 21 of 80 the carrier 14 engages the longitudinal central portion of blade 9 and bridge 10'.

The handle comprises a tubular member 23 provided with a threaded inner wall 24 and a reduced shoulder portion 25, a second tubular member 26 is snugly fitted over said shoulder portion 25. A cap 27 is loosely fitted over the end of member 26, a rod 28 extending through the hollow handle is carried by said cap 27, a portion of said rod 28 is pro- 100

vided with a thread 29 engaging a second threaded inner wall 30 of said member 23, having the parts thus arranged the handle structure is then completed and used as a single unit. The threads 24 of member 23 are adapted to engage threads 12 of screw 6, and upon fitting the handle to the latter, the end 31 of the handle will press against plate 15 until said plate engages base 7 of screw 6 and also the lugs 5' of member 5, thus the handle unit, members 5 and 15 and blade 9 are assembled when the razor is prepared for use.

Upon turning the cap 27, the rod 28 will be caused to travel longitudinally and the end 32 will move upwardly in slot 8 and engage the carrier 14 at 33, pushing said carrier 14 and also the blade 9 upwardly, the base 7 and lugs 5' are so arranged that they keep the edges of members 5 and 15 separated and apart from each other, therefore the edges of said members 5 and 15 do not clamp the edges 9' of blade 9, and due to the space between said edges the edges 9' of said blade 9 are quite free and (during adjustment and flexing of said blade 9) may move freely and be tilted, up or down, in fact to any desired angle between the edges of said members 5 and 15 to vary the fineness of the cut or shave. It will also be noted that due to the special structure of the blade, namely the bridge portion dividing the aperture into two separate openings positioned at each side of the bridge, permits the longitudinal run of the center portion of the blade to be intact, and this is of great importance, because it is the intact center portion that gives the strength to the blade and makes the flexing of the blade perfect and the cutting edge powerful, whereas, if the center run of the blade is punctured, then the base for the strength of the blade is broken and the rest of the blade is just a lifeless mess of metal, that is why many of the present type blades are not satisfactory to the user.

Applicant is hereby pointing out the fact that only in a structure such as applicant shows and describes, wherein sufficient space or room is provided between the edges of the upper and lower clamping members, can the principal idea of adjusting the edges of the blade, without loosening the clamping members, be utilized; as the edges of the blade can then move freely, in or out, up or down, in fact to any desired angle, whereas, if space is not provided between the edges of the upper and lower clamping members, and instead the edges of the blade are clamped tight between the edges of the clamping members, naturally when the center of the blade will be forced upwardly, the edges of the blade will not move into any direction; furthermore, due to the brittleness in each blade as a result of the temper, the edges or part of the edges will break off if they cannot,

on account of being clamped, move freely and be tilted.

From the above it will be seen that I have provided a construction of a few units, namely, a handle unit, a supporting plate unit and a curved member (in fact equivalent to the handle, supporting member and curved member of the present known Gillette type) which can be very easily adjusted, operated and used. And after the parts have been assembled and suitably tightened (by rotation of handle member 26 which, through screw 6, clamps upper member 5 and plate 15 together), the adjusting mechanism 27, 28 and 14 may be operated to vary and tilt the angle of the edges of the blade with respect to the plate 15 and thereby control the smoothness of the shave.

Of course various modifications may be resorted to, for example, Fig. 10; wherein member 23 is externally threaded and over which is fitted a suitable inner threaded tubular member 23'. Upon rotating said tubular member 23', one of its ends will engage the extensions 16 of carrier 14 and move same upwardly with the same force and effect as rod 28, bringing about the same result, even though the rod 28 is eliminated and cap 27 is stationary fitted to the handle. Or, for example, the cap 27 may be threaded on to the handle 26 and the rod 28 suitably guided within the handle.

Although I have mentioned in describing my invention certain parts that may be used, of what material they may be made, and how they may be constructed, yet I desire it to be understood that various changes in detail and modifications may be resorted to without departing from the spirit of the invention.

I claim:

1. A razor blade holder comprising a top member and a plate member, a threaded element mounted on said top member, said element being slotted, a movable carrier permanently mounted in said plate member, said plate member formed with an aperture, a portion of said carrier bridging said aperture and dividing same into two openings, a blade formed with an aperture, a portion of said blade bridging said aperture and dividing same into two openings positioned at each side of said bridging portion, said threaded element passing through said openings in said blade and in said plate member, the bridge portions of said blade and of said carrier being loosely fitted within said slot of said threaded element thereby preventing the rotation of said blade and plate member when positioned on said top member, a hollow handle having its upper end portion threaded, said threaded end portion engaging said threaded element, a part of said upper end portion engaging said plate member, thereby clamping said top end plate members together, a cover member associated with the

other end portion of said handle, a rod carried by said cover member, and upon the rotation of said cover member the end portion of said rod being adapted to engage the bridge portion of said carrier exerts a pressure against said carrier and causes said carrier to flex said blade, thereby causing the edges of said blade to move and be tilted.

2. A razor blade holder as set forth in claim 1, wherein at least a portion of said rod is threaded and engages a threaded portion of said handle whereby upon the rotation of said cover member the rod is forced to move longitudinally.

3. A razor holder as set forth in claim 1, wherein said cover member comprises a rotatable cap loosely fitted over the end portion of said handle covering the open part thereof.

4. A razor blade holder comprising a top member and a plate member, a handle associated with said holder and provided with means to clamp said members together, a blade adapted to be received between said members, means operatively connected with said holder to adjust the inclination of the blade located between said top and plate members while the connection between the handle and said members remains substantially unaffected, means for spacing the edges of said top and plate members a distance greater than the thickness of said blade, thereby permitting the edges of said blade to move freely and be tilted.

5. A razor as set forth in claim 4, wherein said last mentioned means comprising lugs formed on at least one of said members adapted to engage the other member when clamping said members together.

6. A razor blade holder comprising a top member and a plate member adapted to receive a blade therebetween, a threaded element associated with said top member and passing through said plate member, a carrier permanently associated with said plate member, a handle having a threaded portion engaging said threaded element and adapted to exert pressure against said plate member clamping same to said top member, means adapted to exert pressure against said carrier and cause same to flex said blade, and means on said element adapted to limit the movement of said plate member thereby providing space between the edges of the top and plate members to permit the edges of said blade to move freely and be tilted.

7. A razor blade holder as set forth in claim 6, wherein said last mentioned means comprises a base portion on said threaded element larger in diameter than the threaded portion.

8. A razor blade holder comprising a top member having a portion thereof threaded, an apertured plate member, a handle having a threaded portion interfitting with said first mentioned threaded portion of said top member, a part of said handle engaging said plate

member, thereby clamping said top and plate members together, a movable carrier permanently mounted within said plate member, a flexible blade carried between said top and plate members, the edges of said plate member being slotted thereby providing comb portions, means associated with said handle and adapted to exert pressure against said carrier to flex said blade, and means for spacing the edges of said top member away from said comb portions thereby permitting the edges of said blade to move freely and be tilted.

9. A razor blade holder as set forth in claim 8, wherein said first mentioned means comprises a tubular, inner threaded member, rotatably mounted on the outerside of said handle and adapted to engage said carrier.

10. As an article of manufacture, a guard member for a safety razor, comprising a plate having guard portions on at least one of its sides, a carrier mounted on said plate, said carrier having an upper longitudinally extending bar projecting above said plate for engaging a blade, another portion of said carrier adapted to be engaged by an operating means, said carrier having a pair of lugs extending loosely through openings in said plate, a portion of said lugs below said plate being enlarged to prevent detachment of said carrier from said plate while permitting relative movement therebetween.

11. In a holder for a razor blade, a handle, a top member, a plate member having an opening for receiving means for clamping the handle and members together, a carrier having a portion of its body fitted within at least one recess positioned at the side of said opening in said plate member to guide the movement of said carrier, the under edge of said portion being struck down to prevent disengagement of said carrier from said member and means adapted to exert pressure against said carrier.

12. A razor blade holder comprising a top member and a plate member, a portion of said plate member being notched, a carrier loosely fitted within said notched portion and held against complete separation from said plate member, a handle clamping said top and plate members together, means for keeping the edges of said top and plate members apart while said members are being clamped, means operatively connected with said handle for adjusting said carrier without affecting the clamping of said members by said handle, the two members being spaced to such an extent at their outer edges that the marginal portions of a blade placed therebetween are free to be angularly adjusted.

13. As an article of manufacture, a flexible razor blade having at least one cutting edge, a longitudinal groove in the center of the blade, and a pair of apertures adjacent to said groove, one aperture being on each side of said groove.

14. A razor blade holder comprising an upper and lower member adapted to receive a blade therebetween, said upper member having its inner surface dished, the side edges of
5 said dished surface being adapted to receive a portion of the marginal portions of said blade, a portion of the lower member adapted to engage a portion of the blade, a handle operatively associated with said upper mem-
10 ber, a portion of the outer surface of said handle being threaded, a rotatable tubular member interiorly threaded positioned over said handle and engaging the threaded por-
15 tion of same and adapted to move longitudi-
nally of said handle, one end of said rotatable member adapted to engage a portion of said lower member, forcing same to move longi-
tudinally of said handle, pressing the center portion of the blade towards the dished sur-
20 face of said upper member and causing the edges of the blade to move and be tilted, thus adjusting the angle of the edge of said blade.

In testimony whereof I hereunto affix my signature.
